ABSTRACT OF THE DISCLOSURE

A hammer in which a resiliently supported frame is provided with a stamping space and a working chamber in the latter of which is a high pressure gas serving as an energy carrier. A ram located in the stamping space has a hollow rod extending in sealed relation into the working chamber. A hollow piston extends into the rod and a further piston extends into the hollow piston, both pistons being accommodated in a cylinder coupled to said working chamber. Balls seated in the hollow piston engage the rod until released by movement of said further piston.

This invention relates to forging and pressing equipment, and more particularly to high-speed anvilless hammer.

Known in the prior art are high-speed anvilless hammers comprising a frame mounted on a resilient base and incorporating a working chamber and ram, the rod of the latter entering the working chamber. The upper end face of the rod carries an engaging element having the shape of the disc by means of which the ram is retained in starting position owing to the effect of a gas, contained in the working chamber.

The known hammers possess a number of essential disadvantages restricting the field of their application.

Among these disadvantages are the following: the necessity to use a special drive for lifting the ram into the starting position; the lack of the rod working stroke adjustment; a large mass which characterizes the engaging element and which limits the field of application of the hammer, due to the hazard of the rod's longitudinal bending; large consumption of energy when the hammer is in operation.

An object of this invention is to eliminate the above-mentioned disadvantages.

The invention is aimed at the provision of a high-speed anvilless hammer suitable for a wide variety of applications, said hammer permitting of lifting the rod with the working tool, in particular, with the ram, into the starting position by means of an energy carrier, without resorting to a special drive, said hammer further permitting of adjusting the working stroke of the rod.

This object is at least partly achieved by the use of a mechanism intended to adjust the working stroke of the rod which is installed above the working chamber, this adjusting mechanism being so designed that it insures the rod lifting into the starting position by means of the energy carrier contained in the working chamber.

The mechanism for adjusting the working stroke of the rod should preferably have the form of a hydraulic cylinder with a hollow piston, one of its spaces communicating with the working chamber.

It is also preferable that the lower part of the hollow piston have a number of seats accommodating rolling

2

bodies insuring interaction of the hollow cylinder and the engaging element.

The hammer disclosed herein is suitable for performing various operations in connection with the treatment of various blanks (descaling prior to stamping, preliminary upsetting of the blank, stamping of both symmetrical and asymmetrical workpieces, as well as stamping of workpieces in two successive stages without additional heating).

The hammer moreover possesses a stamping space 40% greater than that of the conventionally known hammers, because there is no need for a special drive for lifting the rod into the starting position.

The introduction of the rod stroke adjusting mechanism insures a higher efficiency and output of the hammer.

15 The hammer furthermore has a simpler design, compared with known hammers, is convenient in operation and permits of using the upper tool directly without a ram, for example, a punch which, in turn, insures a higher speed of stamping and improves the accuracy of processing forgings and workpieces.

20 The invention is further disclosed by way of example with reference to the sole figure in the accompanying drawing illustrating a high-speed anvilless hammer according to this invention in longitudinal section.

25 In the drawing, a bed 1 supports a frame 3 installed on shock absorbers 2 and movable along guides 4 in vertical direction.

The frame 3 has a lower port provided with a stamping space 5.

30 Located in the upper part of the frame is a working chamber 6 containing high-pressure gas, and a hydraulic cylinder 7, one of its spaces 8 communicating with the working chamber 6.

A hollow rod 9 of a ram 12 is located in guides 10 and is provided with a seal 11.

35 The ram 12 is movable in a vertical direction in guides 13. In the upper part of the hollow rod 9 there is a bead 14 serving as an engaging element, which retains the rod with the ram in the starting position.

The hydraulic cylinder 7 accommodates a hollow piston 15, its lower part having seats with steel balls 16.

40 The hollow piston 15 accommodates another piston 17, with a circular recess 18 in its bottom part. Passages 19 and 20 connect a space 21 located above the hollow piston 15 and a space 22 located above the piston 17 to the hammer control system (not shown in the drawing).

To deliver an impact, fluid is fed into space 22 through the passage 20 from the pressure pipe (not shown in the drawing). The piston 17 travels downwardly overcoming the resistance of the gas, flowing in from the lower space 8 of the hydraulic cylinder 7. During the movement of the piston 17, the balls 16 slip down into the circular recess 18, thus disengaging the rod 9 of the ram 12 from the hollow piston 15. The ram moves down at a high speed and delivers an impact.

45 Following this, the working fluid is admitted into the space 21 through the passage 19, and the piston 15, overcoming the pressure of the gas, entering the hydraulic cylinder lower space 8 from the working chamber, moves downward. At this stage the piston 17 is still subjected to the pressure of the fluid, while the balls 16 remain in the circular recess 18. Owing to this, the lower part of the hollow piston 15 is allowed to enter the hollow rod 9 of the ram 12. Next, the passage 20 is connected by means of a respective valve of the control system to a drain pipe (not shown in the drawing). The piston 17 actuated by the pressure of the gas admitted from the lower space 8 of the hydraulic cylinder 7 and displacing the fluid from the space 22 now begins moving upwards. The balls 16 come out of the circular recess, and the rod of the ram 12 engages the hollow piston 15.

The passage 19 is connected through a respective valve of the control system to a drain pipe (not shown in the drawing), and the piston 15, together with the ram, under the action of the working gas begins moving upwards, simultaneously displacing the fluid from the space 21.

What we claim is:

1. A high-speed hammer comprising a resilient base, an engaging element, a frame mounted on said resilient base and provided with a working chamber filled with an energy carrier and a stamping space intended to accommodate a working tool and workpiece; a rod with an end face located in the stamping space and carrying said working tool, the rod having an opposite end face located in the working chamber and carrying said engaging element by means of which said rod is retained in a starting position; adjustment means for the adjustment of the rod working stroke, said adjustment means being positioned above the working chamber and enabling lifting of the rod to the starting position by means of the energy carrier contained in the working chamber.

2. A high-speed hammer as claimed in claim 1, in which said adjustment means includes a hydraulic cylinder and a hollow piston in said cylinder, said cylinder being provided with a space communicating with the

working chamber, and a further piston inside said hollow piston and adapted for interacting with the engaging element.

3. A high-speed hammer as claimed in claim 1, in which the hollow piston includes a lower part provided with recesses, said engaging element including rolling bodies at least partly providing the interaction between the engaging element and said further piston.
